METHYLALKANOYLOXYMETHYL KETALS OF
PREDNISOLONE DERIVATIVES

ABSTRACT OF THE DISCLOSURE

Compounds of the formula:

wherein X is H or F and R₁ is an alkyl group having 3 to 5 carbon atoms possess anti-inflammatory action.

This invention relates to anti-inflammatory steroids, particularly prednisolone derivatives. It particularly relates to alkylalkanoyloxy alkyl ketals of fluorinated prednisolone derivatives.

It is previously known to produce alkylalkanoyloxy-alkyl ketals of prednisolone derivatives. These compounds have provided to have good anti-inflammatory effect, particularly when the alkanoyl group contains 1-2 carbon atoms. Tests with other acetals and ketals have shown that the number of carbon atoms in the acetal and ketal group should be low. Known methylalkanoyloxy-methyl ketals are described in e.g. the British Pat. No. 1,020,309 and the Belgian Pat. No. 660,549.

Extensive research work has shown, quite surprisingly and contrary to the usual experiences with acetals and ketals of cortisone derivatives that a greater number of carbon atoms in the alkanoyl group of the ketal gives a considerably improved anti-inflammatory effect in relation to the anti-inflammatory effect obtained with ketals according to the above-mentioned patent. The number of carbon atoms in the alkanoyl group should then be at least 3 and not more than 5.

The compound according to the present invention has the following general formula:

in which R₁ is an alkyl group which has at least 3 carbon atoms and not more than 5 carbon atoms, and in which X designates hydrogen or fluorine.

2

An example is given of the production of one of the compounds according to the above-mentioned formula, and the other compounds are prepared in exactly the same way.

EXAMPLE 1

To a suspension of 300 mg. of triamcinolone in 7.5 ml. of dioxane (dried and newly distilled), 2.5 g. of caprolyoxy-acetone and 25 mg. of 75% perchloric acid are added. The reaction mixture is stirred at 20-30° C. in nitrogen gas atmosphere for 5 hours. Gradually, a homogeneous, acid solution is formed, which is neutralized with a 5% sodium bicarbonate solution to pH 6.5. The solution is extracted with chloroform, after which the chloroform layer is dried and evaporated in vacuum. The reaction is re-crystallized from approx. 10 ml. of a mixture of ethyl acetate and ligroin in the proportion 1:1. Triamcinolone caprolyoxyacetone is obtained, with a yield of 82% and a melting point of 229-230° C.

The melting points of other compounds according to the foregoing general formula are given in the following table:

TABLE 1

25	Corticosteroid derivatives according to the above formula	R ₁	X	Melting point, ° C.
	Triamcinolone butyroyloxyacetoneide	C ₃ H ₇	H	218-220
	Triamcinolone valeroxyloxyacetoneide	C ₄ H ₉	H	210-215
	Triamcinolone caprolyoxyacetoneide	C ₆ H ₁₃	H	229-230
30	Triamcinolone-3,3-dimethyl-butyroyloxyacetoneide	C ₉ H ₁₇	H	207-209
	Fluocinolone valeroxyloxyacetoneide	C ₄ H ₉	F	108-110

The anti-inflammatory effect of the substances according to Table 1 has been compared with triamcinolone acetoxyacetoneide according to the above-mentioned patents according to the granuloma test of adrenalectomized rats. This test was carried out on two series of animals. In one series, the corticosteroids according to Table 1 had been introduced in the animals subcutaneously, while the other series served as a reference. Thereafter, the increases in weight of the used cotton pellets in the animals which had received the corticosteroids were compared with the animals which had not been treated with corticosteroids. A summary of the results of said tests is given in the following table:

TABLE 2

50	No.	Corticosteroid	Daily dose in mg.	Number of animals	Granuloma weight in percent of granuloma weight of reference animals
55	1	Triamcinolone acetyl-oxyacetoneide.	10	48	69
	2	Triamcinolone butyroyloxyacetoneide.	10	8	67
	3	Triamcinolone valeroxyacetoneide.	10	8	50
	4	Triamcinolone caprolyoxyacetoneide.	10	8	64
60	5	Triamcinolone-3,3-dimethyl-butyroyloxyacetoneide.	10	-----	-----
	6	Fluocinolone valeroxyacetoneide.	10	8	62
	7	Triamcinolone acetyl-oxyacetoneide.	3.3	36	83
65	8	Triamcinolone butyroyloxyacetoneide.	3.3	8	87
	9	Triamcinolone valeroxyacetoneide.	3.3	24	73
	10	Triamcinolone caprolyoxyacetoneide.	3.3	16	82
	11	Triamcinolone-3,3-dimethyl-butyroyloxyacetoneide.	3.3	8	99
	12	Fluocinolone valeroxyacetoneide.	3.3	16	75

3

From the above, it is clearly shown that the valeroxyacetones have a considerably better anti-inflammatory effect compared with the other compounds.

We claim:

1. A compound of the formula:

wherein R_1 is an alkyl group containing from 4-5 carbon atoms and X is hydrogen or fluorine.

2. A compound according to claim 1 wherein R_1 is butyl.

3. A compound according to claim 1 wherein R_1 is amyl.

5

4. A compound of the formula
